STOVE DOOR

Filed March 1, 1929

FIG. 1.

FIG. 2.

INVENTOR
PHILLIP A. CELANDER
BY *Dangan Moon*
ATTORNEY

UNITED STATES PATENT OFFICE.

PHILIP A. CELANDER, OF BLOOMINGTON, ILLINOIS, ASSIGNOR TO WILLIAMS OIL-O-MATIC HEATING CORPORATION, OF BLOOMINGTON, ILLINOIS, A CORPORATION OF ILLINOIS.

DESIGN FOR A STOVE DOOR.

Application filed March 1, 1929. Serial No. 30,274. Term of patent 14 years.

To all whom it may concern:

Be it known that I, PHILIP A. CELANDER, a citizen of the United States, residing at Bloomington, in the county of McLean and State of Illinois, have invented a new, original, and ornamental Design for Stove Door, of which the following is a specification, reference being had to the accompanying drawing, forming part thereof.

Figure 1 is a view in front elevation.

Figure 2 is a view in central vertical section of a stove door showing my new design.

I claim:

The ornamental design for a stove door as shown.

PHILIP A. CELANDER.
